United States Patent Office

Des. 185,169
Patented May 12, 1959

185,169

WRITING INSTRUMENT DESK BASE

Kenneth Parker, Janesville, Wis., assignor to The Parker Pen Company, Janesville, Wis., a corporation of Wisconsin

Application April 16, 1958, Serial No. 50,486

Term of patent 14 years

(Cl. D74—1)

FIG. 1

FIG. 2

FIG. 3

FIG. 4

Fig. 1 is a side elevational view of a writing instrument desk base showing my new design;

Fig. 2 is a front elevational view of the same;

Fig. 3 is a top plan view thereof; and

Fig. 4 is a front perspective view thereof on smaller scale.

I claim:

The ornamental design for a writing instrument desk base, substantially as shown.
